UNITED STATES PATENT OFFICE.

JAMES P. PERLEY, OF WASHINGTON, DISTRICT OF COLUMBIA.

DESIGN FOR CAMPAIGN-BADGE.

Specification forming part of Design No. **6,015**, dated July 30, 1872.

Specification describing a Design for Campaign-Badges, invented by JAMES P. PERLEY, of the city of Washington, District of Columbia.

The nature of my design is fully represented in the accompanying illustration, to which reference is made.

A represents the apple-tree, the body of my design, while B B refer to forms for photographic or other likenesses of Grant and Wilson; attached below, C is a form having the word "Appomattox," and date, "April, 1865."

The design of the campaign-badge consists of a tree, with the portraits or pictures, motto, and date, substantially as set forth.

I reserve the right to stamp them in sheet metals, *papier-maché*, or other suitable mate-

rial; or engrave the design for the printing of ribbon-badges, heading of circulars, &c.; or wherever else it may be desirable to print the same. I reserve the right to stamp and engrave my design plain, or in colors, according to the purpose for which it shall be used. I prefer to follow nature in the coloring, making the foliage green, the trunk a dark drab or brown, and the fruit red, or red and white.

What I claim as my invention is—

The design for a campaign-badge, consisting of the tree, portraits or pictures, motto, and date, substantially as set forth.

JAS. P. PERLEY.
